(57) **CLAIM**

The ornamental design of a lipstick, as shown and described.

DESCRIPTION

FIG. 1 is a perspective view of a lipstick showing the new design.

FIG. 2 is a front view of the invention shown in FIG. 1, the front view and the rear view are the same and thus there is only one view presented; and,

FIG. 3 is a side view of the invention shown in FIG. 1, with the left and right side views being identical mirror images of each other.

The broken lines, shown in the figures, depict portions of the lipstick that form no part of the claimed design.
